(57) **CLAIM**

The ornamental design for an electric pressure cooker, as shown and described.

DESCRIPTION

1. Electric pressure cooker

1.1 : Front

1.2 : Back

1.3 : Left

1.4 : Right

1.5 : Top

1.6 : Bottom

1.7 : Perspective

1.8 : Perspective

1 Claim, 8 Drawing Sheets(56)
